SLUG CASTING MACHINE

Ransom H. Turner, Great Neck, N. Y., assignor to
Mergenthaler Linotype Company, a corporation
of New York

Application August 2, 1945, Serial No. 608,406

6 Claims. (Cl. 199—60)

1

This invention is directed specifically to certain improvements in the slug casting machine shown and described in my co-pending application Serial No. 464,011, filed October 31, 1942, now Patent No. 2,542,599, dated February 20, 1951.

In that machine, a single slotted mold of less than standard height is employed, and the matrices, whose characters range in size from 6 pt. to 72 pt., are formed in their casting edges with routing notches of a depth to compensate for the reduced height of the mold so that slugs cast therein will be of the required "type height." The width of the mold cavity is 12 pt. and the slugs produced therein from matrix characters of greater point sizes will be of the L-shaped or T-shaped variety, their overhanging type bearing portions being cast in the routing notches of the matrices. The metal pot is stationary and, when the machine is at rest, the mold occupies a position directly in front of the mouthpiece of the pot in casting relation thereto. The matrices are composed in a hand stick and, prior to the inauguration of a machine cycle, the hand stick with its composed line of matrices is pushed endwise into a receptacle wherein the matrix line is located properly with reference to the end walls of the mold slot. The receptacle is slidably mounted in a reciprocable wedge block by which it is moved downwardly and upwardly to carry the matrix line to and from the casting position, and means are employed to arrest the receptacle at different predetermined levels so as to locate the matrix characters of different point sizes in the proper position transversely of the mold slot. When the machine cycle is inaugurated, the wedge block is pulled downwardly by spring tension to force the line receptacle and mold rearwardly in effecting the necessary "lock-up" preparatory to the descent of the pot plunger; and, after the casting operation, the wedge block is raised to its original position to move the receptacle forwardly and disengage the matrix line from the mold and also, through certain auxiliary connections, to move the mold forwardly out of contact with the pot mouthpiece. As the machine cycle continues, the line receptacle is raised and the mold swung forwardly and downwardly to a horizontal position of rest upon a fixed support where, first, the base of the slug is trimmed by a horizontally reciprocable knife and, then, the slug is ejected from the mold by the operation of a vertically reciprocable ejector blade. Thereafter, and as the machine cycle is completed, the mold is swung back to its original position in front of the mouthpiece of the metal pot, ready for the next casting operation.

2

Referring to the present improvements: The mold, wedge block, pot plunger and ejector blade are all operated pneumatically under the control of an air valve manifold and a set of timing cams associated therewith. As another departure, the ejector slide is operable through the medium of a pair of toggle devices which carry the ejector blade and are adapted, prior to the active stroke of the slide, to advance the blade relatively thereto so as to increase the initial pressure exerted upon the base of the slug in breaking its adherence to the side walls of the mold cavity. As still another departure, after the casting of the slug, the mold is movable vertically downward in its own plane in order to shorten the radius of its swinging movements and thus permit it to clear the line receptacle which, in the present instance, remains permanently at the casting level. As a result of this particular improvement, the automatic means for raising and lowering the receptacle have been dispensed with entirely and the wedge block has been given a much better support during the casting operation. As a further departure, there are employed several safety devices connected directly to a specially constructed control device for the main driving clutch and functioning to cause a disengagement of the clutch, and thus stop the operation of the machine, under certain abnormal conditions that may arise during a machine cycle.

The details of construction, and the manner in which the parts cooperate to bring about the results desired, will best be understood from the description to follow.

35 In the accompanying drawings, the improvements have been shown merely in preferred form and by way of example, and therefore it should be understood that the invention involved is not limited to any specific form or embodiment except insofar as such limitations are specified in the appended claims.

Referring to the drawings:

Fig. 1 is a side elevation of the improved machine, partly broken away to show the driving and control mechanisms;

Fig. 2 is a front elevation, also broken away, to show the manual control connections;

Fig. 3 is a top plan view;

Fig. 4 is a vertical section through the metal pot taken on the line 4—4 of Fig. 3 and showing certain movable parts associated with the pot in their normal position;

Fig. 5 is a vertical section similar to Fig. 4 but showing the movable parts in a different position;

Fig. 6 is a detail horizontal section taken on the line 6—6 of Fig. 4;

Fig. 7 is a vertical section through the casting and ejecting mechanisms;

Fig. 8 is a vertical section taken on the line 8—8 of Fig. 7;

Fig. 9 is a detail face view of the adjusting devices for the hand stick receptacle;

Fig. 10 is a side elevation, partly in section and partly broken away, showing part of the casting mechanism in the "lock-up" position and also part of the operating means for the wedge block and the mold;

Fig. 11 is a side elevation showing the wedge block raised and also the means through which the safety attachments for the mold and hand stick are controlled;

Fig. 12 is a vertical section taken on the line 12—12 of Fig. 11, showing the hand stick in proper position in the receptacle;

Fig. 13 is a detail vertical section taken on the line 13—13 of Fig. 11;

Fig. 14 is an elevation similar to Fig. 10 but showing the mold after being lowered from the casting station and the operating means therefor;

Fig. 15 is an elevation similar to the lower portion of Fig. 14 but showing the mold swung to its horizontal position in rear of the ejecting station;

Fig. 16 is an elevation similar to Fig. 15 but showing the mold advanced to the ejecting station;

Fig. 17 is a detail vertical section taken on the line 17—17 of Fig. 15;

Fig. 18 is a front elevation of the ejecting mechanism, showing by the full lines the parts in their normal position and by the dotted lines the toggle connections between the ejector slide and ejector blade straightened out to advance the blade relatively to the slide;

Fig. 19 is a front elevation similar to Fig. 18 but showing the relative position of the parts during the ejection of the slug from the mold;

Fig. 20 is a horizontal section taken on the line 20—20 of Fig. 18;

Fig. 21 is a face view, on an enlarged scale, of the control device for the main driving clutch and parts associated therewith;

Fig. 22 is a vertical section taken on the line 22—22 of Fig. 21;

Fig. 23 is a horizontal section taken on the line 23—23 of Fig. 21;

Fig. 24 is a detail fragmentary elevation showing the means controlling the safety attachment for the wedge block;

Fig. 25 is a plan view, partly in section, of the starting and stopping mechanism and the pneumatic control devices; and

Fig. 26 is a time chart indicating the order in which the various organs and safety attachments of the machine are intended to function during a cycle of operation.

The matrices X and the hand stick Y (Fig. 12) are similar to those used in the machine shown and described in my co-pending application previously identified, the matrices being formed with relatively deep routing notches x which extend completely across their casting edges, and the hand stick comprising, generally, the two upper and lower side members Y¹, Y² and the two end walls Y³, Y⁴. The matrix characters x¹ are punched in the bottoms of the routing notches and, irrespective of their point size, are positioned for "base alignment" with reference to a com-

mon datum line when the matrices are supported by their lower edges. The lower side member Y² of the hand stick is formed with a guide rail y adapted to engage corresponding notches formed in the lower edges of the matrices, and the upper side member Y¹ is provided with a matrix aligning bar (not shown) attached thereto in such manner that when moved endwise in opposite directions it will be cammed downwardly and upwardly into and out of engagement with the upper edges of the matrices.

The hand stick also includes a pair of abutments or banking blocks Y⁵, Y⁶, arranged respectively adjacent the end walls Y³, Y⁴ and, like the matrices, notched in their lower edges to engage the guide rail y. The abutment Y⁵ is appropriately connected to the free end of a clamping screw Y⁷ mounted in the end wall Y³, whereas the abutment Y⁶ at its upper end is attached to the aligning bar and normally held yieldingly in spaced relation to the end wall Y⁴ by a compression spring y¹ so as to be capable of sufficient lost motion to actuate said bar. After a matrix line is completely composed in the hand stick, it is shifted to the right (Fig. 12), against the influence of the spring y¹, by means of the clamping screw and thereby locked in place between the abutments Y⁵ and Y⁶ as the latter banks against the end wall Y⁴, the aligning bar at the same time being forced down into engagement with the matrices to effect their alignment upon the guide rail y.

The hand stick with its composed line of matrices now is pushed endwise from the right (Fig. 3) into a horizontally disposed channel or receptacle A and up against a fixed stop a, where it is held in place by a retaining detent a¹ mounted in the receptacle and adapted to engage a corresponding recess formed in the upper side wall of the hand stick. The receptacle A (Fig. 14) is arranged directly in front of a mold B and mounted by tongue and groove connections a² in a reciprocable wedge block or clamping member C, so as to be capable of vertical adjustment relatively thereto in locating the matrix characters of different point sizes in the proper casting positions transversely of the mold slot.

The vertical adjustments of the receptacle A are effected by the partial rotation of a rock shaft A¹ (Fig. 8), mounted at its opposite ends in the opposed side members D¹, D² of a fixed U-shaped bracket D, and equipped with a pair of spaced-apart cam elements a³ upon which the receptacle is supported. To insure perfect control of the receptacle by said elements at all times, it is held yieldingly upon the same by an overlying spring actuated lever A² pivotally mounted in a small subsidiary bracket d fastened to the side member D¹ of the larger bracket D. As shown best in Figs. 3 and 13, the lever A² includes a relatively long horizontally disposed arm A³ and a shorter offset vertical arm A⁴, the former being provided with an anti-friction roller a⁴ engaging the upper edge of the receptacle, and the arm A⁴ being opposed to a compression spring a⁵ seated in a recess d¹ formed transversely in the bracket member D¹.

Operation of the rock shaft A¹ is controlled manually from a turning knob or handle E, and the corresponding adjustments of the receptacle A are accurately determined by a circular dial plate E¹ having appropriate markings adapted to be read in conjunction with a pointer E² fastened to the other side member of the U-shaped bracket D. Both the knob E and dial plate E¹

are secured to a small stub shaft E³ which is rotatably mounted in the bracket member D² and operatively connected with the rock shaft A¹ through a pair of small spur gears e. A spring plunger or detent e¹, also mounted in the bracket member D² and arranged to engage one or another of a series of properly spaced-apart apertures or recesses formed in the dial plate, prevents accidental displacement of the latter and, through the intervening connections, maintains the adjusting cam elements in their different angular positions.

The clamping member or wedge block C (Figs. 3 and 10) includes a horizontal body portion C¹ and a pair of integral end plates C², which latter extend above the body portion and are formed with tongues c inclined slightly rearward from top to bottom and engaging corresponding grooves d² formed in the opposed side members D¹ and D² of the bracket D. The rear vertical face of the wedge block fits against the vertical front wall of the receptacle A, while the front face thereof is inclined at the same angle as that of the tongues c so as to have a sliding fit with a corresponding inclined surface d³ formed on the rigid cross member D³ of the bracket D. The side members D¹, D² of the bracket D (Figs. 1 and 3) extend forwardly from a metal pot F in the vicinity of the mouthpiece F¹ thereof and are bolted to the pot casing F², which in turn is rigidly supported upon a flat top plate O of the machine frame.

At the start of a machine cycle, the wedge block C is moved downwardly and forces the receptacle A rearwardly across the supporting cam elements a³ to press the matrix line against the mold B and at the same time squeeze the latter against the mouthpiece of the metal pot F in effecting a positive "lock-up" preparatory to the casting operation. Conversely, upon the upward or return movement of the wedge block which takes place immediately after the casting operation, the mold and mouthpiece F¹ will be relieved of the lock-up pressure and the receptacle will be pulled forwardly to its normal position to carry the matrix line out of contact with the face of the mold. To conserve time between cycles, the hand stick, if desired, now may be removed from the machine and another one substituted therefor before the cycle is completed. It may also be mentioned at this point, and as indicated by the dotted lines in Fig. 3, that the mouthpiece of the metal pot F, like the one shown in my copending application, is supported independently of the pot by lugs d⁴ projecting inwardly from the side members D¹ and D² of the bracket D, so that the pressure created by the casting operation will be absorbed entirely by said bracket between the lugs at the rear and the cross member D³ at the front and, therefore, may be as great as the tensile strength of the bracket will permit.

Operation of the wedge block C (Figs. 3, 10 and 11) is effected from a vertically movable, pneumatically controlled rack bar C³ through a horizontal shaft C⁴ and a pair of gear wheels C⁵, which latter are mounted on the shaft and are arranged in mesh with corresponding sets of rack teeth c¹ formed on the end plates C² of the wedge block. The shaft C⁴ (Fig. 3) is journaled in spaced-apart bearing blocks d⁵, d⁶ of the bracket D and is provided with a driving pinion C⁶ meshing with the rack bar C³. The operating means for the rack bar C³ include an air cylinder C⁷ arranged above the driving pinion C⁶ and supported by a bracket plate D⁴ secured to one of a

pair of integral flanges D⁵, D⁶ projecting forwardly from the cross member D³ of the U-shaped bracket D. A double acting piston C⁸ is mounted in the cylinder C⁷, and the rack bar C³ (Figs. 10 and 11) is formed integrally with the piston rod, the latter projecting downwardly through the lower end of the cylinder and being properly guided in a fixed bearing bracket d⁷ located adjacent the pinion C⁶.

The piston C⁸ is controlled by an adjustable two-way slide valve C⁹ (Fig. 25) which is one of several comprising a manifold R and which is adapted to admit air under pressure through separate pipe lines c² and c³ into the bottom and top of the cylinder to move the piston C⁸ upwardly and downwardly, respectively. The manifold R is arranged alongside the main shaft S below the top plate O and includes, generally, a body portion R¹ and a cap portion R², the former being secured by side flanges R³ to stationary brackets O¹, O² of the machine frame, and the cap portion being formed with a chamber R⁴ into which air from a pressure tank R⁵ (Fig. 1) is admitted through a supply pipe R⁶ and directed to the pipe line c² or c³ according to the adjusted position of the slide valve C⁹. As air enters one end of the cylinder C⁷, it is exhausted from the other through a recess in the valve and a communicating exhaust passage (not shown) formed in the body portion of the manifold. The construction of the manifold R and slide valves is similar to that fully shown and described in the patent to J. C. Plastaras No. 2,840,842, so that any further description here would be superfluous.

The mold B (Figs. 7, 8 and 14 to 16 inclusive) is detachably fastened to the cross member of a bail-like support B¹ and is capable of vertical movement to and from its normal position in guideways d⁸ formed in the side members of the bracket D and adapted to accommodate corresponding tongues b projecting from the opposite ends of the mold. The side arms B² of the support B¹ depend from the cross member B³ thereof and are connected with an underlying shaft B⁴ through the medium of a pair of toggle devices B⁵, each comprising a crank arm B⁶ keyed to the said shaft and a link B⁷ attached to the contiguous side arm B² at a point adjacent the cross member B³. The shaft B⁴ (Figs. 8 and 14) is mounted in a fixed stand bracket D⁷ and is rotatable by means of a spur gear B⁸ fastened thereon and arranged midway between the two crank arms B⁶. As shown best in Figs. 7 and 8, the bracket D rises from the top plate O of the machine frame and is adapted to give additional support to the bracket D through a rigid cross bar D⁸ fastened to the lower edges of the flanges D⁵, D⁶. For reasons about to appear, the side arms B² of the mold support are formed with elongated slots b¹ engaging corresponding fulcrum studs d⁹ which are axially aligned with the shaft B⁴ and project inwardly from the opposite side members of the U-shaped bracket D. The toggle devices B⁵ also include a pair of relatively strong spring detents b² attached to the lower ends of the links B⁷ and normally engaged with the slots b¹ at points above the studs d⁹.

After the casting of a slug and the return of the hand stick receptacle A to its normal position, the shaft B⁴ is given a one and one-quarter rotation. During the first 180° of rotation, the toggle devices B⁵ will be collapsed and the mold, under their control, will be lowered until the tongues b clear the lower ends of the guideways

d^8 and the upper ends of the vertical slots b^1 of the mold support engage the fulcrum studs d^9 . Meanwhile, the detents b^2 , as a result of the collapsing of the toggles, first will be forcibly disengaged from the slots b^1 and then caused to engage them again at points below the fulcrum studs, so that the toggles may regain their control over the movements of the mold. As the shaft B^4 continues its rotation the mold, through the connecting detents, will be swung by the toggles forwardly and downwardly from its vertical position shown in Fig. 14 to the horizontal position shown in Fig. 15. Then, as the toggles are straightened out, the mold will be moved directly forward to the ejecting station, where the slug is pushed out of the mold by the operation of a vertically reciprocable ejector slide G (Fig. 16). Thereafter, the rotation of the shaft B^4 is reversed and, through the same connections, the mold first will be withdrawn from the ejecting station, then swung upwardly and rearwardly to register its tongues with the vertical guideways d^8 , and finally restored to the casting station in front of the pot mouthpiece F^1 .

The mold is arrested in the horizontal position shown in Fig. 15 by its engagement with a pair of small angle plates d^{10} projecting rearwardly from the rigid cross bar D^8 and serving to locate the tongues b of the mold in engaging relation to corresponding fore-and-aft grooves d^{11} , the latter being formed in the front flanges D^5 , D^6 of the main bracket D and adapted to guide the mold in its movements to and from the ejecting station. During the forward movement of the mold, the base of a slug cast therein is trimmed by a stationary knife H ; and when the mold stops in the ejecting position (Figs 16 and 18), it will be properly located and supported between the flanges D^5 , D^6 , upon the cross bar D^8 . The knife H (Figs 7 and 10) is secured to the lower end of the bracket D and is capable of a limited adjustment, toward and from the mold B , by a pair of set screws h arranged at the opposite ends of the knife.

Rotation of the shaft B^4 (see Figs. 7 and 8) is effected by the operation of a reciprocable pneumatically controlled rack bar B^9 , through an intermediate shaft B^{10} and two multiplying gears B^{11} and B^{12} mounted thereon. The shaft B^{10} is journaled in the stand bracket D^7 (before referred to) and arranged directly below the shaft B^4 , the gear B^{11} meshing with the rack bar B^9 , and the gear B^{12} meshing with the spur gear B^8 . As best shown in Fig. 7, the rack bar B^9 is slidably mounted in suitable guideways b^3 extending longitudinally of a horizontally-disposed fore-and-aft air cylinder B^{13} which is arranged directly behind the stand bracket D^7 and secured to the main supporting plate O . As indicated by the dotted lines in Fig. 7, the cylinder B^{13} is equipped with a piston B^{14} whose rod B^{15} extends forwardly through and beyond the front end wall of the cylinder, where it is appropriately fastened to the contiguous end of the rack bar B^9 . Operation of the piston B^{14} is controlled from the manifold R by a two-way slide valve B^{16} adapted, at the proper moments, to admit air under pressure through pipe lines b^4 , b^5 into the rear and front ends of the cylinder B^{13} to move the piston and attached rack bar forwardly and backwardly, respectively. In this way, the shaft B^4 is rotated in opposite directions and the mold shifted to and from the casting and ejecting stations in the manner already described.

The reciprocable ejector slide G (Figs. 18 to

20 inclusive) is arranged between the two front flanges D^5 , D^6 of the bracket D and is formed with a pair of vertically disposed side members G^1 , which latter are connected together by an integral offset web portion G^2 and provided with tongues g extending longitudinally thereof and engaging in corresponding grooves or guideways d^{12} formed in said flanges. The ejector slide G is equipped, as usual, with an ejector blade G^3 but, according to the present invention, the blade instead of being attached directly to the slide is carried by a horizontal subsidiary slide bar G^4 , the latter (Fig. 20) being arranged between the vertical side members G^1 of the ejector slide and connected thereto by tongues and grooves g^1 in order to be capable of a limited vertical movement in relation to the slide.

In the preferred embodiment illustrated (see also Fig. 7), the slide bar G^4 is operated by a pair of pneumatically controlled toggle devices G^5 , each comprising a lever g^2 and a link g^3 , the former being pivoted to the upper end of the contiguous side member G^1 of the ejector slide, and the latter connecting the shorter arm of said lever to one end of the bar G^4 . An adjustable banking screw g^5 , arranged to engage the upper edge of the web portion G^2 , limits the upward movement of the ejector slide, and a lug g^6 projecting forwardly from the web and overlying the bar G^4 , limits the upward movement of the bar and thus locates the ejector blade in its normal or slug ejecting position (Fig. 18). The longer horizontal arms of the toggle levers g^2 are appropriately connected with the stem of a piston G^6 which is mounted in an upright air cylinder G^7 secured to the main bracket D and arranged directly above the ejector slide G .

Operation of the piston G^6 is controlled from the manifold R through a slide guide G^8 and air lines g^7 , g^8 leading from the manifold to the opposite ends of the cylinder G^7 . Normally, air pressure in the bottom of the cylinder sustains the ejector slide through the medium of the bar G^4 and toggle devices G^5 (now partially collapsed) in its raised position shown in Fig. 18, with said bar engaging the lug g^6 and with the web portion of the slide engaging the banking screw g^5 . However, as soon as the air pressure is reversed to the top of the cylinder through the pipe line g^7 , the toggle devices G^5 will be straightened out and force the ejector blade G^3 downwardly far enough to overcome the initial resistance presented to the blade at the start of the slug ejecting operation. As the toggles are straightened out, the shorter arms of the levers g^2 are adapted to bank against the contiguous side members of the ejector slide G and thereby establish a positive connection between the slide and the piston G^6 , so that the latter by its continued downward movement may impart a full active stroke to the ejector blade for the complete ejection of the slug from the mold. As a slug is ejected, it passes through an elongated clearance aperture d^{13} , formed in the rigid cross bar D^8 , and is received by an underlying conveniently located trough or galley D^9 fastened to the rear wall of the aperture. Air now is exhausted from the top of the cylinder G^7 through the pipe line g^7 and re-admitted under pressure at the bottom through the pipe line g^8 . In rising, the piston G^6 will first collapse the toggle sufficiently to raise the subsidiary slide bar G^4 into engagement with the projecting lug g^6 of the web G^2 and then, as it continues its

upward movement, restore the ejector slide to its original position against the banking screw g^5 .

The use of toggle devices for imparting the initial stroke to the ejector blade is particularly advantageous when, as herein, the blade is operated pneumatically. As well understood in the art, the greatest pressure which the ejector blade must exert is at the start of the slug ejecting operation when it is called upon to break the adhesion of the slug with the mold; thereafter, the resistance offered by the slug is much less and little more than is required for the slug trimming operation. It is evident, therefore, that a much smaller pneumatic piston may be used with the toggle devices than without them.

Reference is now directed to Figs. 1, 2, 4 and 5 which illustrate the mechanism controlling the operation of the pump plunger during the casting period. The plunger F^3 is mounted, as usual, to reciprocate in a well F^4 of the pot crucible and is operated pneumatically by an overhead double acting piston F^5 , to which it is connected by a vertical link f arranged between the plunger and a block f^1 attached to the lower end of the piston rod. The piston F^5 (Fig. 4) is mounted in an upright air cylinder F^6 and controlled from the manifold R by a two-way slide valve F^7 adapted to admit air under pressure through pipe lines f^2, f^3 into the top and bottom of the cylinder to operate the piston. As best shown in Figs. 4 and 7, the cylinder F^6 is supported upon the horizontal cross member of a bail-shaped bracket F^8 rising from the pot casing; and at its opposite ends the cylinder is closed by caps f^4, f^5 , the lower cap f^5 being drilled transversely to accommodate the piston rod and the usual gland f^6 for the necessary air-tight connection.

In order that a maximum pressure may be created in the top of the cylinder preparatory to the metal injecting operation, the piston F^5 is positively sustained in its raised position (Fig. 4) by a retractable latch pin F^9 , slidably mounted in a fixed bracket F^{10} for a limited endwise movement into and out of the path of a tooth or lug f^7 formed on the block f^1 of the piston rod. Retraction of the latch pin F^9 to release the piston is effected, in opposition to a pull spring f^8 , by the partial rotation of a short fore-and-aft rock shaft F^{11} journaled in a small bearing bracket F^{12} and provided with a vertical arm F^{13} connected to the latch pin through an intermediate horizontal link F^{14} . A tip screw f^9 , threaded into the bracket F^{10} and engaging a corresponding slot formed in the latch pin, holds it against angular displacement and insures its proper engagement with the lug f^7 . The rock shaft F^{11} is also provided with a depending crank arm F^{15} , operable by the upper arm of a vertically disposed lever F^{16} (Fig. 1) pivoted midway between its ends in the machine frame and controlled by an edge cam S^1 which is mounted on the main shaft S and arranged to engage an anti-friction roller f^{10} carried by the lower arm of said lever.

When the pump plunger F^3 descends under the pressure created above the piston F^5 , molten metal from the pot throat will be forced into the mold from the rear and up against the composed line of matrices at the front, the extent of the downward movement of the plunger being determined by the volume of metal it displaces in filling the mold and the routing notches of the matrices as well as the slight air space existing in the throat in the vicinity of the mouthpiece F^1 . However, it is important that the plunger be allowed to partake of its full active stroke before

the "lock-up" pressure is relieved. For this purpose, the pot crucible is equipped with a pressure release valve I of the fluted variety (Figs. 4 and 5) for controlling a port f^{11} located between the pot well and the crucible and through which the molten metal in the throat and crucible is maintained at a common level. In the preferred embodiment illustrated, the port f^{11} is formed in the upper wall of the pot well and the valve I is mounted therein for a limited vertical movement. When the valve is pushed downwardly, a solid portion thereof is adapted to close the port but, when raised, the fluted section thereof allows the metal in the crucible to pass into the well and throat.

The means herein employed for operating the valve I include a small upright air cylinder I^1 supported by the bracket F^8 and equipped with a piston I^2 which is connected with the valve by a long vertical link I^3 . Operation of the piston I^2 , like the other pistons previously described, is controlled from the manifold R by a two-way slide valve I^4 adapted, in one position, to admit air through a pipe line i into the bottom of the cylinder I^1 to force the piston upwardly and, in the other position, to admit air through a pipe line i^1 into the top of the cylinder to force the piston downwardly. The upward movement of the piston I^2 is limited by a collar i^2 on the piston rod, and the downward movement thereof is limited by the engagement of the top of the pressure release valve with the upper wall of the pot well. The movements of the controlling slide valve I^4 are so timed that, just before the latch pin F^9 is withdrawn to release the pump piston F^5 , the piston I^2 will descend to close the valve I and thus permit metal in the throat of the pot to be projected into the mold under the maximum pressure and speed by the initial drop of the pump plunger F^3 . The piston I^2 then rises to open the valve I and permit the plunger to complete its active stroke, the air pressure in the bottom of the cylinder I^1 being maintained to keep the valve open throughout the rest of the cycle.

Referring now to Fig. 25, each of the several slide valves of the manifold R is connected by an intervening rocker arm R^7 to one of a corresponding number of bell-crank levers R^8 mounted on a common pivot rod r and arranged between the side flanges R^3 of the manifold. The levers R^8 are equipped with anti-friction rollers r^1 and are operable by a set of timing cams S^2 keyed to the main shaft S and engaging the rollers r^1 . While the cams S^2 have not been shown in detail, it readily will be understood that they will vary in form so as to actuate the slide valves at the proper moment during the machine cycle to charge the individual air cylinders with which they are connected and thus bring about the operation of the different organs of the machine in their proper order or sequence.

The driving mechanism and control devices of the improved machine will now be described, reference being made to Figs. 21 to 25 inclusive. The cam shaft S is mounted at its opposite ends in stationary bearing brackets O^3, O^4 of the machine frame and receives its motion from a hollow fore-and-aft drive shaft J through the medium of a friction clutch K and a train of reducing gears, the latter including, generally, a large gear J^1 mounted to rotate on a fixed stub shaft J^2 and meshing with a driving pinion J^3 , a small gear J^4 secured to the hub of the gear J^1 , and a larger gear J^5 keyed to the cam shaft S and meshing with the gear J^4 . The clutch K

(Fig. 25) comprises two opposing members K^1 and K^2 , the former being integral with a motor driven wheel K^3 mounted to rotate on the drive shaft J , and the latter being splined to the rear end of said shaft and attached to a push rod K^4 which is mounted in the drive shaft and movable endwise therein to carry the clutch member K^2 into and out of engagement with the clutch member K^1 . The engagement of the clutch members is effected by a compression spring K^5 seated in the shaft J behind a collar k of the push rod K^4 , and the disengagement thereof is effected by a lever J^6 having one of its arms engaging the front end of the push rod. The lever J^6 (Fig. 25) is pivoted between its ends in a fixed bracket J^7 and is operable by a clutch control device L mounted on the cam shaft S and arranged alongside the other arm of said lever.

In the present instance, the device L (as will be noted in Figs. 21 and 22) includes a straight member L^1 splined to the shaft S for axial movement thereon, and a second disk-like member L^2 rotatably mounted on said shaft. The member L^2 is adapted to be driven by the member L^1 through the medium of two pairs of opposed cam plates l^1 , l^2 arranged diametrically opposite each other and held yieldingly together by the lever J^6 under the influence of the clutch spring K^5 . To sustain the member L^2 against axial movement by the spring K^5 , the control device L further includes a circular frame plate L^3 supported on the shaft S and held rigidly against angular displacement by an integral projecting ear l^3 bolted to the machine frame. At one side, the plate L^3 is formed with a hub portion l^4 which banks against the contiguous end bearing for the shaft S , and at its opposite side, it engages a narrow spacing hub l^5 of the member L^2 . The two members L^1 and L^2 of the device L are also capable of a limited rotary movement in relation to each other as permitted by a pin-and-slot connection l^6 ; and a pull spring l^7 (Fig. 21), anchored to the member L^1 and connected to the member L^2 , tends constantly to turn the latter counterclockwise within the limitations allowed by said connection.

When the machine is in motion, the member L^2 will rotate with the driving member L^1 but, if the rotation of the former should be arrested, the member L^1 will be displaced axially by the cam plates l^1 , l^2 and, through the lever J^6 , cause a disengagement of the main driving clutch K . At such times, the pull spring l^7 will be extended, due to the slight rotary movement of the member L^1 in relation to the member L^2 and will later, when the member L^2 is released, act to restore the parts to their original relative position to permit a re-engagement of the clutch.

In starting and stopping the machine under normal conditions, the arresting means employed (Figs. 21 and 22) include a retractable plunger M mounted in an offset vertical housing portion L^4 of the circular plate L^3 and movable a limited distance into and out of the path of a single tooth or lug l^8 formed on the outer edge of the clutch control member L^2 . Operation of the plunger M is controlled by a conveniently located crank handle N and is effected in opposition to a compression spring m arranged in the housing L^4 above a collar m^1 of the plunger and reacting against a cap or nut l^5 screwed onto the housing. The handle N (Figs. 1 and 2) projects above the top plate O of the machine frame through a slot o therein and is attached at its lower end to a horizontal rock shaft N^1 disposed beneath the

plate O and provided with an arm N^2 which is connected with the plunger M through an intermediate vertical link N^3 . When the machine is at rest, the parts are adapted to occupy the position shown in Figs. 21 and 25, with the tooth l^8 of the clutch control member L^2 banking against the lower end of the plunger M , and with the member L^1 displaced by the cam plates l^1 , l^2 , to effect the disengagement of the driving clutch K . However, to inaugurate a machine cycle, it is merely necessary to pull the crank handle N forwardly within the limitations of the slot o , and then release it. By this operation, the plunger M is raised out of engagement with the tooth l^8 and allowed to drop in behind it under the influence of its spring m , the member L^2 of the device L meanwhile having been turned by the pull spring l^7 counterclockwise the slight distance necessary to permit the engagement of the main clutch K . As the cycle is completed the tooth l^8 will again engage the plunger M to stop the operation of the machine in the manner already described.

It may be desirable on occasion, and for reasons unnecessary to mention, to stop the operation of the machine at any time during the cycle and, to this end, means operable independently of the automatic control device L are employed for disengaging the driving clutch K . Such means (Figs. 1 and 2) include a pair of toggle links N^4 operable by the crank handle N through a second arm N^5 on the rock shaft N^1 and a vertical link N^6 . One of the links N^4 is anchored to a fixed projection o^1 of the machine frame, while the other is attached to a slide block k^1 mounted on the push rod K^4 and located directly behind the collar k (see also Fig. 25). With this arrangement, by pushing the handle N rearwardly from its normal or vertical position shown in Fig. 1, the toggle will be straightened out and, through the engagement of the block k^1 with the collar k , the rod K^4 will be forced forwardly in position to the compression spring K^5 and cause a disengagement of the driving clutch K , the toggle under such conditions serving to lock the clutch out of action until it is again collapsed by restoring the handle N to its original position. To permit the operation of the toggle N^4 , the vertical link N^3 (Fig. 1) is formed with a slot n so that the arm N^2 , which controls the toggle, may move relatively thereto. At this time it may also be stated for the sake of clearness that, due to the sliding connection between the toggle and the push rod K^4 , the former will present no interference to the operation of the handle N and rock shaft N^1 in raising and lowering the plunger M .

The improved machine also is equipped with a plurality of safety attachments associated with different organs of the machine, and all of said attachments are connected with the control device L in such manner as to cause a disengagement of the main driving clutch K when any one of the organs fails to function properly. In the preferred embodiment illustrated (Figs. 21, 22 and 23), the safety attachments include, in part, a plurality of retractable stop pins or plungers, numbered 1 to 6 inclusive, mounted in the fixed circular frame plate L^3 , and a corresponding plurality of studs, numbered 1^a to 6^a inclusive, projecting laterally from the disk-like driven member L^2 of the clutch control device L . The plungers 1 to 6 are disposed at different radial distances from the center of the plate L^3 ; and while the corresponding studs, 1^a to 6^a , are similarly disposed about the member L^2 , they are spaced circumferentially from the plungers at varying de-

grees (see Fig. 26) according to the operating time of the machine organs during a cycle.

Except for plunger 1, the form and manner of mounting the plungers 1 to 6 are identical, so that a description of one should suffice for all. Thus, the plunger 4 (Fig. 22) is mounted transversely in the plate L³ and held yieldingly by a compression spring 7 in its active position, with one end protruding from the inner side face of the plate into the path of the stud 4^a. The spring 7 is arranged in a recess 7^a formed in a boss or lateral protuberance of the plate L³ and engages an integral collar 8 of the plunger, which banks against the bottom wall of the recess and locates the plunger in its active or protruding position. The retraction of the plunger 4 is effected through the medium of a Bowden wire 9 attached to the other end of the plunger and having its tubular covering 10 anchored in the customary way to the said protuberance by a hexagon clamping nut or cap 10^a. While the flange 11 of the covering might serve as a seat for the spring 7, the latter (Fig. 22) preferably reacts against a spacing disk or ring 12 interposed between the flange and the end of the protuberance.

Operation of the plunger 4 is controlled by the mold B as it is moved in the manner previously described to and from the ejecting station, the means employed (see Figs. 7, 18 and 20) comprising a short horizontal rock shaft 13 having two depending arms 14 and 15, the former being equipped with an adjusting screw 16 disposed in the path of the mold, and the latter being operatively connected to the plunger through the Bowden wire 9. If the mold properly reaches the ejecting position, the plunger 4, by operation of the rock shaft, will be retracted out of the path of the stud 4^a; otherwise, the plunger will remain undisturbed in its active position and cause a disengagement of the main clutch K by stopping the rotation of the member L² through its engagement with said stud. Danger of breakage or serious damage to the ejecting mechanism, the operation of which (Fig. 26) immediately follows the arrival of the mold at the ejecting station, is thus averted.

As the mold is restored to its vertical position of rest in front of the pot mouthpiece F¹, it is also adapted to control, in precisely the same way, the movements of the safety stop plunger 6 in order to stop the operation of the machine and thus prevent a metal squirt, that likely would take place at the beginning of the next cycle, through failure of the mold to attain such a position. Thus, the plunger 6 is connected by a Bowden wire 17 (Figs. 3 and 11) to an arm 18 projecting forwardly from one end of a rock shaft 19 arranged above the mouthpiece of the metal pot and mounted in a suitable bearing bracket 20. At its opposite end, the rock shaft is provided with a second arm 21 equipped with an adjusting screw 22 disposed directly over and in the vertical path of the mold B. As the mold in rising approaches its uppermost position, it will engage the adjusting screw 22 and, through the intermediate connections, withdraw the stop plunger 6 out of the path of the corresponding stud 6^a; and when the mold is lowered during the next cycle, it will break its engagement with said screw and permit the plunger, under the influence of its spring, to resume its active position.

To avoid the production of imperfect or porous slugs and the attendant difficulties that likely would arise if the closing of the pressure relief valve I failed to take place before the drop of the

pump plunger F³, there is employed (Figs. 4 and 5) a small bell-crank lever 33 controlled by the operation of the valve and having one of its arms connected by a Bowden wire 34 to the safety stop plunger 2. The lever 33 is pivotally mounted on a fixed bracket 35 and is operable by a lug 33^a projecting laterally from the upper extremity of the valve link I³ and which is arranged to engage the other arm of said lever. When the piston I² descends to close the valve, the lever will be actuated by the lug 33^a and, through the Bowden wire 34, retract the plunger 2 from the path of the corresponding stud 2^a. However, if for any reason the valve piston fails to function properly, the clutch control device L will automatically stop the operation of the machine as the member L² is arrested by the engagement of the stud 2^a with the plunger 2.

Similarly, the safety stop plunger 3 is controlled by the pump plunger F³ as it completes its downward or active stroke. In this case, the stop plunger 3 is connected by a Bowden wire 36 to one arm of a small bell-crank lever 37 (Figs. 4 and 5) pivoted at the lower end of the latch pin bracket F¹⁰ and having its other arm disposed below and in the vertical path of the lug or tooth f⁷ previously referred to. After the casting of a slug and the pump plunger is allowed to descend to its lowermost position (see the dotted lines in Fig. 5), the tooth f⁷ is adapted to actuate the lever 37 so as to withdraw the stop plunger 3 from the path of stud 3^a, but if the pump plunger should be arrested in its descent and the lever not be actuated, disengagement of the main clutch will be effected by the engagement of the stud 3^a with the stop plunger 3.

A safety attachment is also provided for stopping the operation of the machine in the event the ejector slide is not raised high enough, after the slug ejecting operation, for the attached blade G³ to clear the mold B as the latter is withdrawn from the ejecting station. Said safety attachment (Figs. 7, 18 and 19) includes a small bell-crank lever 41 pivoted to the front guiding flange D⁶ of the U-shaped bracket D and having one of its arms connected through a Bowden wire 42 to the retractable stop plunger 5 of the clutch control device L. The other arm of the lever 41 is equipped with an adjusting screw 43 located above and in the vertical path of the contiguous upright side member G¹ of the ejector slide G, so that the lever will be rocked in the proper direction to retract the stop plunger 5 from the rotary path of the corresponding stud 5^a as the slide G completes its upward movement. If, however, anything should interfere with the normal operation of the ejector slide, the plunger 5 would remain in the path of the stud 5^a and, by arresting the driven member L² of the control device, cause disengagement of main clutch K before the mold B starts its retreat from the ejecting station.

The excepted stop plunger 1 (Fig. 21) is mounted in a radially disposed housing L⁶ rising from the outer edge of the frame plate L³ and which is similar in form to the housing L⁴ for the plunger M. At its lower end, the plunger 1 is cut away to present a squared off banking surface 23 to one or the other of two studs 1^a and 1^b projecting laterally from the member L² and which are located, respectively, at 30° and 180° from said banking surface as indicated in Fig. 21. Under normal conditions, the plunger 1 is lowered and raised twice during a machine cycle to locate a clearance notch 24, formed transversely in its

lower end, first in registry with the stud 1^a and later in registry with the stud 1^b , whereby the two studs may escape contact with the banking surface 23 and thus permit the cycle to proceed without interruption. The raising and lowering of the plunger 1 is controlled by the operation of the vertically reciprocating wedge block C , the latter (Figs. 3, 7 and 24) being provided with a small cam plate 25 adapted, as the wedge block is moved upwardly and downwardly, to actuate a rock shaft 26 mounted in a bracket d^4 secured to the righthand bearing d^3 for the gear shaft C^4 . The cam plate 25 is formed with two high portions, 27 and 28 , respectively, and an intermediate low portion 29 ; and the rock shaft, at one end, is provided with a depending crank arm 30 arranged to ride over the cam plate. At its opposite end, the rock shaft 26 is provided with a depending arm 31 connected to the plunger 1 by a Bowden wire 32 .

Normally the plunger 1 is sustained against the pressure of its spring (not shown) in the raised or inactive position shown in Fig. 21 by the high portion 27 of the cam plate 25 . However, when a machine cycle is inaugurated and the wedge block descends to its lowermost position in effecting the "lock-up," the plunger first will be lowered and then raised to locate the notch 24 in registry with the stud 1^a as the arm 30 of the rock shaft rides over the cam plate 25 and engages the high portion 28 thereof. As the cycle proceeds and the wedge block is restored to its uppermost position, the plunger again will be lowered and raised in the same manner to locate the notch 24 in registry with the stud 1^b . It will now be seen that, unless the wedge block completes its downward stroke as required or during its return stroke reaches its uppermost position out of the path of the facewise movements of the mold B , the rotation of the clutch control member L^2 will be arrested by the engagement of the stud 1^a or 1^b with the banking surface 23 of the plunger and stop the operation of the machine in the manner before described.

There is one other safety attachment yet to be described, namely, one for preventing the inauguration of a machine cycle unless the hand stick Y is inserted properly into the receptacle A .

This hand stick safety attachment (Fig. 21) includes a retractable spring-actuated plunger 38 mounted in a radially disposed housing L^7 similar in form to the housings L^4 and L^8 and which likewise rises from the outer edge of the frame plate L^3 of the clutch control device L . The plunger 38 in effect constitutes a stop pawl for the driven member L^2 , being movable automatically into and out of engagement with a series of ratchet teeth l^{11} formed on the periphery of the said member and offset rearwardly from the single tooth or stop lug l^8 before referred to. Operation of the plunger 38 is controlled by a small bell-crank lever 39 pivoted to a lower extension of the fixed bearing bracket d and connected to the plunger by a Bowden wire 40 . As best shown in Fig. 12, the location of the lever 39 is such that, when the hand stick Y is pushed home in the receptacle A against the stop plate a , the lever will be actuated by a pin y^2 projecting laterally from the end wall Y^4 of the hand stick and, through the wire 40 , disengage the plunger 38 from the ratchet teeth l^{11} so as to permit the machine cycle to be inaugurated in the manner already described. However, if the hand stick should be improperly inserted in the receptacle or later become dislodged therein, or if an attempt were

made to remove it from the receptacle prior to the casting operation, the plunger immediately will function to stop the operation of the machine, by arresting the member L^2 of the clutch control device L , and thereby avert the danger of a metal squirt. In this connection, it may be stated that since the casting operation is completed during the first 180° rotation of the main shaft, as indicated on the time chart shown in Fig. 26, the hand stick thereafter may safely be removed from the receptacle A if desired in order to save time in composition; it being observed (Fig. 21) that the ratchet teeth of the member L^2 extend only half-way round the periphery thereof and permit the plunger 38 to ride freely and idly over the intervening plain surface l^{12} during the last 180° of rotation.

While the time chart shown in Fig. 26 is probably self-explanatory a brief description thereof may be helpful. The vertical lines of the chart indicate in increments of 30° a complete cycle of rotation of the cam shaft, and the cross lines indicate the operating time of the several organs of the machine during the cycle. The first cross line from the top indicates that the hand stick Y must be left in the receptacle A throughout 180° of rotation of the cam shaft, but that it may be removed from the receptacle at any time during the second 180° of rotation. The second line indicates that the wedge block C is given its active or clamping stroke during the first 30° of rotation of the cam shaft, then maintained in its clamping position during the next 120° of rotation of the cam shaft, then restored to its original or inactive position during the next 30° of rotation, and finally left at rest in its upper or inactive position for the remaining 180° of rotation of the cam shaft. In this connection it will be noted that the safety stop plunger 1 is inactive throughout the time the wedge block occupies its lower clamping position, as well as throughout the time it occupies its upper non-clamping position, but that it will be effective at any other times, which means that the stop plunger 1 will be active if the wedge block fails to reach either its clamping or its non-clamping position. The third line indicates that the pot vent valve is moved to its closed position during the first 22° of rotation of the cam shaft, then maintained in its closed position during the next 38° of rotation, and then fully restored to its open position after the cam shaft has completed 90° of its rotation, remaining in that open position throughout the remaining 270° of the cam shaft's rotation. The fourth line indicates that the pump plunger is allowed to drop at the conclusion of 45° of rotation of the cam shaft, then allowed to exert full pressure on the molten metal during the next 35° of rotation, then allowed to partake of its full stroke during the next 60° of rotation, then restored to its uppermost position just prior to the time the cam shaft completes one-half of its full rotation, being maintained in said uppermost position throughout the remainder of the cam shaft's rotation. In this connection it may be noted that the stop plunger 3 is active at all times throughout the cycle of operation except when the pump plunger reaches its lowermost position, it being remembered that at that time, and only at that time, will the stop plunger be withdrawn to inactive position. The fifth line indicates that the mold remains in casting position throughout the first 180° of rotation of the cam shaft, then moved downwardly to ejecting position when the shaft has rotated 230° , re-

maining in that position until the shaft has rotated 300°, and then restored gradually to its casting position, reaching that position when the cam shaft has completed 350° of rotation, and remaining so positioned for the last 10° of rotation. In this connection it will be noted that the stop plunger 4 is active at all times except when the mold is in the ejecting position and that the stop plunger 6 is active at all times except when the mold is in the casting position, which means that the operation of the machine will be arrested if the mold, when set in motion, fails to reach the ejecting position or later on the casting position. The sixth line indicates that the ejector remains in its raised or inactive position throughout 240° of rotation of the cam shaft, then operated to eject the slug throughout the next 20° of rotation, and finally restored gradually to its raised or inactive position where it remains during the last 70° of rotation of the cam shaft. In this connection it may be noted that the stop plunger 5 is inactive so long as the ejector is in its raised or inactive position but becomes active during the slug ejecting stroke so as to arrest the operation of the machine if the ejector fails to complete that stroke.

For purposes of mobility, the improved machine, as shown best in Figs. 1 and 2, preferably is supported upon rollers or casters o^2 secured to the rectangular base plate O^5 of the frame structure beneath the top plate O ; and to enhance the general appearance of the machine, the casting and control mechanisms as well as the pressure tank, motor and air compressor are all enclosed in a paneled compartment located between said plates.

Having thus described my invention, what I claim is:

1. In a slug casting machine, the combination of a metal pot, a hand stick receptacle located at all times at the casting level, a slug ejecting mechanism arranged directly in front of the receptacle, a mold disposed between the metal pot and the hand stick receptacle, said mold normally occupying a vertical plane at the casting station and movable downwardly in said plane to a position clear of the hand stick receptacle, fixed vertical guideways in which the mold is slidably mounted and which are cleared by the mold when it completes its downward movement, a mold support mounted to swing the mold from its downwardly moved position facewise to a horizontal plane aligned with the ejecting station, fixed horizontal guideways in which the mold is slideable forwardly from its downwardly swung position to the ejecting station, and automatic means operable after the casting operation to effect such downward, facewise and forward movements of the mold.

2. A combination according to claim 1, wherein the automatic means include a rotatable shaft journaled in fixed bearings, and a toggle connection between said shaft and the mold support, said toggle connection by the rotation of the shaft acting first to effect the downward movement of the mold by a rectilinear movement of the mold

support and thereafter to effect the forward movement of the mold by a rectilinear movement of the mold support.

3. A combination according to claim 2, wherein the mold support is provided with depending arms formed with elongated slots in which are arranged fixed fulcrum studs located in axial alignment with the rotatable shaft, said slots in co-operation with the fulcrum studs determining the downward movement of the mold and then affording a fulcrum for the mold support as the latter is swung to effect the facewise movement of the mold.

4. A combination according to claim 1, wherein the automatic means include a rotatable shaft journaled in fixed bearings, a toggle connection between said shaft and the mold support, said toggle connection by the rotation of the shaft being first collapsed to effect the downward movement of the mold, and thereafter extended to effect the horizontal movement of the mold to the ejecting station, and a coupling device actuated by the rotatable shaft for effecting the facewise swinging movement of the mold after the toggle connection is collapsed and before it is extended.

5. A combination according to claim 4, wherein the automatic means include a power-actuated reciprocatory member operable to rotate the shaft in one direction in moving the mold from casting to ejecting position and then operable to rotate the shaft in the opposite direction to restore the mold from ejecting to casting position.

6. A combination according to claim 1, wherein the automatic means include a power-actuated reciprocatory member operable in one direction in moving the mold from casting to ejecting position and then operable in the opposite direction to restore the mold from ejecting to casting position.

RANSOM H. TURNER.
